BUILDING BLOCK

William Clukie, Bay City, Mich.

Application September 22, 1949, Serial No. 5,140

Term of patent 3½ years

(Cl. D18—2)

To all whom it may concern:

Be it known that I, William Clukie, a citizen of the United States of America, residing at Bay City, in the county of Bay and State of Michigan, have invented a new, original, and ornamental Design for a Building Block, of which the following is a specification, reference being had to the accompanying drawing, forming part thereof.

In the drawing:

Fig. 1 is a perspective view of a building block, showing my new design.

Fig. 2 is a top plan view thereof.

Fig. 3 is an end-elevational view.

I claim:

The ornamental design for a building block, as shown.

WILLIAM CLUKIE.
